UNITED STATES PATENT OFFICE

GEORGE E. NERNEY, OF ATTLEBORO, MASSACHUSETTS, ASSIGNOR TO BAY STATE OPTICAL COMPANY, OF ATTLEBORO, MASSACHUSETTS, A CORPORATION OF MAINE

DESIGN FOR A FRONT FOR A SPECTACLE FRAME

Application filed May 26, 1930. Serial No. 35,767. Term of patent 14 years.

To all whom it may concern:

Be it known that I, GEORGE E. NERNEY, a citizen of the United States, and a resident of Attleboro, in the county of Bristol, State of Massachusetts, have invented a new, original, and ornamental Design for a Front for a Spectacle Frame, of which the following is a specification, reference being had to the accompanying drawings forming a part hereof.

In which,

Figure 1 is a front elevation of a front for a spectacle frame showing by new design,

the essential feature of which is the open and rearwardly curved endpiece, and

Figure 2 is a top plan view of the parts shown in Figure 1.

I claim:

The ornamental design for a front for a spectacle frame as shown and described.

In testimony whereof, I have signed my name to this specification this 20th day of May, 1930.

GEORGE E. NERNEY.
